UNITED STATES PATENT OFFICE

115,619

DESIGN FOR A MILK BOTTLE CARRIER

William A. Goodwin, Lincoln, Nebr.

Application March 10, 1939, Serial No. 83,494

Term of patent 7 years

To all whom it may concern:

Be it known that I, William A. Goodwin, a citizen of the United States, residing at Lincoln, in the county of Lancaster and State of Nebraska, have invented a new, original, and ornamental Design for a Milk Bottle Carrier, of which the following is a specification, reference being had to the accompanying drawing, forming part thereof.

The figure is a view in perspective of a milk bottle carrier showing my new design.

I claim:

The ornamental design for a milk bottle carrier, as shown.

WILLIAM A. GOODWIN.
